US00D903401S

(12) **United States Design Patent** (10) **Patent No.:** **US D903,401 S**
(45) **Date of Patent:** **** Dec. 1, 2020**

(54) **FOOD PROCESSOR**

(71) Applicant: **Spectrum Brands, Inc.**, Middleton, WI (US)

(72) Inventor: **Darek J. Koszylko**, Dane, WI (US)

(73) Assignee: **Spectrum Brands, Inc.**, Middleton, WI (US)

(**) Term: **15 Years**

(21) Appl. No.: **29/696,591**

(22) Filed: **Jun. 28, 2019**

(51) LOC (12) Cl. **31-00**

(52) U.S. Cl.

USPC **D7/386; D7/376; D7/378**

CLAIM

The ornamental design for a food processor, as shown and described.

DESCRIPTION

FIG. 1 is a front perspective view of a food processor showing my new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines within the shaded area represents features that form no part of the claimed design. The broken lines depicting the remainder of the food processor form no part of the claimed design.

1 Claim, 6 Drawing Sheets
